UNITED STATES PATENT OFFICE.

CHARLES H. SMOOT, OF MAPLEWOOD, NEW JERSEY.

COMBUSTION-CHAMBER-PRESSURE REGULATOR.

Application filed July 31, 1925. Serial No. 47,293.

The present invention has for its object the regulation of the pressure of the gases in a furnace in such manner and by such means as will insure the maintenance at 5 all times of the proper degree of negative pressure with respect to the atmosphere independently of fluctuations of other functions such as thickness of fuel bed; pressure of forced draft or the like. It is desirable that the pressure increase its negative value 10 with increase in furnace rating, i. e. with increase in air volume.

The combinations described and claimed herein accomplish these objects by a control 15 of the stack or outlet damper which control is responsive to the pressure of the gases in the furnace; devices responsive to the pressure of the furnace gases, properly proportioned, or properly loaded, are so connected to the stack or outlet damper as to give the same a definite pressure adjustment 20 for each rating of the furnace to the end that as the air volume increases, the pressure in the furnace will be increased in 25 negative value in quadrature, that is to say, if for example the rating and hence the air volume is doubled the negative pressure is quadrupled. A chief advantage flowing from this condition is that the leakage 30 through the furnace walls will always be inward and its amount proportional at all times to the furnace rating, the leakage being greater as the furnace becomes hotter, which is conducive both to economy and 35 durability. The heat released will be carried off quicker as the rating increases and in that way the brick work will be protected against any soaking effect. A principal 40 feature of the invention is a duplex damper control, one element of which is made responsive to the pressure just above the fire and the other element responsive to the pressure just ahead of the stack damper, the latter element being designed to act 45 jointly with the former element for the purpose of giving a movement to the damper and effect the increase in negative pressure above referred to. As the pressure in the stack is more negative than in the fire box, 50 its control element is made smaller or has its force reduced so that it will not have an exaggerated influence on the control, and means are provided for accurately adjusting its effect.

An application of the invention is shown 55 in the accompanying drawings in which—

Figure 1 is a diagrammatic sectional view of a boiler furnace.

Figure 2 is a diagram showing the ordinary relation between the combustion chamber pressure and the stack pressure, and

Figure 3 is a similar diagram showing how this relation is changed by the application of my regulator.

A boiler 1 has a combustion chamber 2, 65 a stack 3 provided with a stack damper 4, and an air supply pipe 5 in which is shown a damper 6 as a means of controlling the volume of air admitted to the furnace.

The stack damper 4 is connected by crank 70 arm 7 and 8 and lever 9 to a rod 10 attached to a diaphragm 11 operating in a casing 12. The lever 9 is pivoted to a fixed support at 13 and may have an adjustable loading means as for example a spring 14, the 75 tension of which may be changed by screw 15. The rod 10 may have a piston 16 operating in a cylinder 17 to act as a retarding device. The chamber 17' above the diaphragm is connected by pipe 18 to the combustion chamber 2 while the chamber 19 below the diaphragm is connected by pipe 20 to the stack just below the stack damper. A pipe 21 leads off from pipe 20 to the atmosphere and furnishes a means of reducing 80 the suction in pipe 20 and therefore also in chamber 19. Cocks 22 and 23 in the air inlet pipe 21 and the stack pressure pipe 20 respectively furnish means for fractionating the suction in the stack to the desired amount so that the pressure in chamber 19 will balance the combustion chamber pressure existing in chamber 17. Thus if it is desired to have the suction in the stack ten times the suction in the combustion 85 chamber, then the valve 23 is partly closed and the valve 22 partly opened until the pressure in chamber 19 is one-tenth of the pressure in the stack.

The operation is as follows:

With the furnace rating at a minimum, the stack damper will be nearly closed, the draft will be slight, and the pressure in the combustion chamber will be but slightly less than atmosphere. An increase in air supply 100 to the fire following an increased demand on the furnace will initially raise the pressure in the combustion chamber a slight 105

amount, thus reducing the suction on top of the diaphragm. The diaphragm will then move to open the damper. Such opening of the damper will be followed by an increase 6 in the suction below the damper and also an increase in suction but of less amount just above the fuel bed. A small proportion of the increase in suction below the damper will be communicated to the underside of the dia- 10 phragm and this will cause the damper to open still further and thus give a suction in the combustion chamber greater than if the latter pressure alone was the controlling element. By adjusting the cocks 22 and 23, 15 any fraction of the stack suction can be allowed to pass to the underside of the diaphragm and thus the desired increase in negative pressure can be obtained, the ideal conditions being formed when the suction 20 increases as the square of the furnace rating. It will be understood that with the new setting of the damper thus brought about by a change in furnace rating, the diaphragm will again be in equilibrium but with slightly 25 greater suction on its top side, and consequently in the furnace over the fire, and also a correspondingly greater suction on its underside corresponding to a fraction of the much greater suction in the stack below the 30 damper.

It will be seen that the furnace pressure control is held at the proper negative value irrespective of all other variables having to do with the operation of the furnace. 35 The fuel bed may be thick or thin; the pressure of the forced draft may be great or small; the controller will insure the negative pressure quite independently of them and independently of their means of control, 40 but will always give an increasing negative furnace pressure corresponding to an increasing rating and air volume supply. The mathematical relations may be illustrated by the diagrams Figures 2 and 3.

45 In these figures the vertical dimensions indicate the suction or negative pressure with respect to the atmosphere while the horizontal dimensions indicate the load or boiler rating. In ordinary practice the combustion chamber pressure is maintained at a fixed negative value, as shown by the horizontal line $c_c p$ of Fig. 2. The negative stack pressure as shown by the curve increases with the square of the rating. 50 Figure 3 shows the result on the combustion chamber pressure when the regulator described above is in operation. Here the negative combustion chamber pressure $c_c p$ is also increased as the square of the rating; 55 the curves a, b, c , representing the fluctuations of the stack pressure having corresponding curves a, b, c , for the combustion chamber pressure. P_1 being the combustion chamber pressure, P_2 the stack pressure, and 60 K a constant, then the boiler differential

$(P_2 - P_1)$ is connected to the rating R of the boiler by formula

$$P_2 - P_1 = \bar{R}^2 x K.$$

The regulator introduces into this equation the qualification element by moving the stack damper until

$$\frac{P_2}{P_1} = n \text{ or } P_2 = n P_1$$

70 where n is the ratio desired to be maintained between the two pressures. By substituting the equivalent of P_2 in the formula we have:

$$n P_1 - P_1 = \bar{R}^2 x K = P_1(n-1)$$

80 or

$$P_1 = \left(\frac{K}{K-1} \right) \bar{R}^2 = C \bar{R}^2$$

85 so that P_1 becomes a definite function of $\bar{R}^2$. In other words the combustion chamber pressure varies in exact proportion with the square of the boiler rating.

I have shown in the accompanying drawings a preferred arrangement of apparatus for regulating furnace pressure, but it is to be understood that the mechanism itself is capable of many variations. It will, for example, be evident to anyone skilled in the art that there are many alternative ways of reducing the stack pressure to bring it down in force to a point where it can be made to balance the combustion chamber pressure. 95

I claim:

1. A furnace pressure control comprising an outlet damper, means responsive to combustion chamber pressure, and to a fraction of the pressure just preceding the damper to control the setting of the said damper to effect a variation in the negative pressure in the combustion chamber in greater ratio than the variation in the furnace rating. 105

2. A furnace pressure control comprising an outlet damper, means responsive to combustion chamber pressure, and to a fraction of the pressure just preceding the damper to control the setting of the said damper to effect a variation in the negative pressure in the furnace proportional to the square of the 110 furnace rating.

3. A furnace pressure control comprising a stack damper, a chamber connected by pipe with the combustion chamber and having a moving member responsive to the pressure in said chamber connected to the damper, a chamber connected by pipes with the stack to the pressure in which said moving member is also responsive so that the pressures in the chambers act oppositely on the member, and means for reducing the force of the stack pressure to establish a definite ratio between the combustion chamber pressure and the pressure in the stack. 115

4. A furnace pressure control comprising 120

100

105

110

115

120

125

130

5 a stack damper, a chamber connected by pipe with the combustion chamber and having a moving member responsive to the pressure in said chamber connected to the damper, a chamber connected by pipes with the stack to the pressure in which said moving member is also responsive so that the pressures in the chambers act oppositely on the member, and means for fractioning the stack 10 pressure before it reaches its connected chamber, said means comprising an adjustable outlet to the atmosphere from the pipes connecting the stack with the chamber.

15 5. A furnace pressure control comprising a stack damper, a chamber connected by pipe with the combustion chamber and having a moving member responsive to the pressure in said chamber connected to the damper, a chamber connected by pipes with the stack to the pressure in which said moving member is also responsive so that the pressures in the chambers act oppositely on the member, means for fractioning the stack pressure 20

before it reaches its connected chamber, said means comprising an adjustable outlet to 25 the atmosphere from the pipes connecting the stack with the chamber, and an adjusting valve in the connecting pipe for restricting the flow to the stack from the atmosphere.

30

6. A furnace pressure control comprising a damper for the regulation of furnace pressure which is responsive to furnace pressure on the one hand and a second pressure intermediate between that of external atmosphere 35 and stack pressure of the furnace whereby an adjustable negative pressure is maintained in the combustion chamber.

7. A furnace pressure control comprising means for varying the furnace pressure 40 actuated by means responsive to the furnace pressure and to some other pressure intermediate between the stack pressure and atmosphere.

CHARLES H. SMOOT.
